Primary Examiner—Sandra L. Morris*Assistant Examiner*—Monica A. Weingart*Attorney, Agent, or Firm*—Jacqueline S. Larson[57] CLAIM

The ornamental design for a bag, as shown and described.

DESCRIPTION

FIG. 1 is a perspective view a bag, showing the new design; FIG. 2 is a front view thereof;

FIG. 3 is a right side elevational view, the left side being a mirror image except for the seam and round fasteners.

FIG. 4 is a rear view thereof; and,

FIG. 5 is a bottom plan view thereof.

The purse not shown in the interior of the bag, which is not drawn, forms no part of the claimed design.
